UNITED STATES PATENT OFFICE.

CARL MOSEN AND WILLIAM J. COLEMAN, OF BEND, OREGON.

TRANSFER TABLE FOR SAWMILLS.

Application filed March 10, 1926. Serial No. 93,655.

This invention relates to improvements in transfer tables for sawmills, having for an object to provide a device for moving the sawed boards from the usual or standard design of transfer table for sawmills and directing the same into engagement with the conveyor means of a trimmer or trimming table, whereby the ends of said boards will be trimmed, that is, properly squared and cut to the desired length, the device being of such construction as to permit its operator to accurately position or adjust the board to be trimmed with respect to the first of the usual series of trimmer saws during the time of actual transfer of said board from the transfer table onto the trimmer, hence, insuring proper trimming thereof and also, eliminating the need of two men for this transfer of the board onto the trimmer, and the proper positioning of such board for trimming, thereby effecting a saving in time and labor overhead expense.

Another and equally important object of the invention is to provide a transfer table of the standard design with an auxiliary transfer means or device operable to remove the board to be trimmed from the transfer table and at the same time, to elevate it to a position from which it can be readily skidded onto the trimmer table, the board during this skidding transfer from the device onto the trimmer, being so arranged as to permit of easy and convenient adjustment thereof to a position whereat it will be properly trimmed, by a single operator or attendant.

Yet another object of the invention is to provide the auxiliary transfer device with a simple and efficient form of control means therefor, whereby said auxiliary transfer may be operated at will by the single operator for removing and elevating the board to be trimmed from the transfer table prior to its actual transfer to the trimmer means, hence, permitting ample time to be had for effecting proper positioning of the board with respect to the trimming saws.

Other objects of the invention will be in part obvious and in part pointed out hereinafter.

In order that the invention and its mode of operation may be readily understood by persons skilled in the art, we have in the accompanying illustrative drawings, and in the detailed following description based

thereupon, set out one possible embodiment of the same.

In these drawings:

Figure 1 is a top plan view of portions of the adjacent ends of a standardized transfer table and trimmer with my improved auxiliary transfer device installed thereupon.

Figure 2 is a side elevation of the same showing the operating and control means for the auxiliary transfer device, and,

Figure 3 is a fragmentary horizontal section taken on the line 3—3 of Figure 2, looking in the direction in which the arrows point.

Having more particular reference to the drawing, in connection with which like characters of reference will designate corresponding parts throughout, it may be stated for convenience at this time, that our improved auxiliary transfer device is especially adapted for installation upon the accepted and standard type or design of transfer table generally indicated herein by the numeral 1, such transfer table being provided with a series of relatively spaced parallel conveyor chains 2 operated by suitable means, not shown herein; it being understood that certain of the ends of such conveyor chains are received about sprocket wheels 3 carried upon a shaft mounted transversely of one end of the transfer table 1 as is clearly shown in the Figure 2. Suitable super-supporting structure generally designated by the numeral 4 is provided the transfer table 1, while adjacent to the discharge end thereof and supported upon other supporting structure 5 is the receiving end of the usual trimmer of a standard design of sawmill; this trimmer serving to receive the sawed boards from the transfer table 1 whereupon such boards are engaged by conveyor chains generally designated by the numeral 6 and carried longitudinally over such table into engagement with series of rotary trimmer saws generally indicated at this time by the numeral 7. In this way, it will be understood by workers skilled in the art that the sawed boards received from the transfer table 1 have their ends properly squared prior to the cutting of the same to the desired length.

In this transfer of sawed boards from the transfer table 2 to the trimmer aforesaid, it has heretofore been the custom to place two men or operators at either end of that space

occurring between the adjacent ends of the transfer table and the trimmer table, it being the duty of these men to lift the boards from the transfer table and to direct the same onto the conveyor chains 6 of the trimmer, properly adjusting the boards so transferred so that certain of the ends thereof will be adjusted with respect to the first saw 7 of the series thereof that the end of the board will be properly squared when cut to the desired length. An operation such as this, obviously, entails considerable expense and with a view toward reducing such expense, our improved auxiliary transfer device is employed.

The improved auxiliary transfer device may be stated to comprise an inclined runway 8 disposed transversely of the discharge end of the transfer table 1 in the manner shown in the Figures 1 and 2 the upper and outer end of the runway 8 being supported upon standards 9, which standards in turn, have journal boxes or bearings 10 secured to the upper and outer sides thereof whereby to rotatably support a transversely disposed shaft 11 carrying thereon suitably spaced sprocket wheels 12 over which the ends of endless conveyor chains 13 are passed, the said endless conveyor chains 13 being extended transversely of the inclined runway and in substantial parallelism to the conveyor chains 2 of the transfer table proper to points below the table as is shown in the Figure 2, whereupon they are received about sprocket wheels 14 mounted upon suitable stub shafts journaled in bearings provided upon diagonally disposed supporting arms or brackets 15 extended from the said runway 13. Also, in this connection, it is to be noted that the upper portion of the runway 8 is arranged in a substantially horizontal plane as is indicated by the numeral 16, thus serving to carry the board to be trimmed from the discharge end of the transfer table 1 subsequently to its elevation to a point thereabove. It is likewise of moment to note at this time, that the lower and inner chains 13 of the auxiliary transfer device are not only arranged in substantially parallelism to the conveyor chains 2 of the transfer table 1 but that they are disposed in slight overlapping relationship with respect thereto in the manner clearly shown in the Figure 1. Because of this overlapping as between the adjacent or meeting ends of the conveyor chains 2 and 13, it will be readily appreciated that sawed boards passing from the chains 2 will be immediately engaged and conveyed further on from the discharge end of the transfer table 1 by means of the said conveyor chains 13. By consequence, there will be no interruption in the course of movement of the sawed boards over and from the transfer table 1.

Angularly formed skid bars or arms 17

are provided in the improved device, the upper ends of the said bars being so formed as to be arranged in planes corresponding to the plane in which the upper end of the runway 8 is arranged, as indicated by the numeral 16; these said upper ends of the skid bars 17 being provided with downwardly disposed fingers adapted to be engaged in bracket gears 18 extended from immovable brackets or extensions 19 carried upon the upper end of said runway 8. The lower or remaining ends of the skid bars 17 are extended into engagement with the adjacent or receiving end of the table of the trimmer of the sawmill and thus, it will be appreciated that boards delivered onto the said horizontal portions of the skid bars 17 will be caused to move thereover onto the downwardly inclined portions and from thence, directed onto the trimmer table for engagement by the endless conveyor chains 6 whereupon they are then conveyed into engagement with the trimming saws 7 aforesaid. These skid bars 17 are disposed longitudinally with respect to the transfer table and the trimmer of the sawmill and also, are arranged in relative parallel relation as is clearly shown in the Figure 1. Because of the fact that the horizontal portions of said bars are arranged in a plane above the adjacent or receiving end of the trimmer, it will be understood that boards delivered thereonto will move by gravity downwardly over the downwardly inclined portions of said bars, during which period of movement they may be adjusted thereon so as to be properly positioned with the first saw 7' of the series of trimmer saws 7. Because of this adjustment of the sawed boards during the time of their skidding from the runway 8 onto the receiving end of the trimmer, it will be understood that certain of their ends may be so positioned as to be accurately squared at the time of cutting of the same into the desired length by the various trimming saws.

With a view toward providing the endless conveyor chains 13 of the auxiliary transfer device with a means for imparting motion thereto, a sprocket wheel 20 is mounted upon one portion of the transversely extending shaft 11 and has a sprocket chain 21 engaged thereabout, said sprocket chain passing downwardly into engagement with and over a sprocket wheel 22 mounted upon a driven shaft 23 journaled in suitable bearings 24 upon a supporting frame work 25 at a point below the auxiliary transfer device. This driven shaft 23 is provided with a gear 26 normally meshing with a pinion 27 fixedly mounted upon the adjacent end of a shiftable countershaft 28, one end of which is mounted in a suitable bearing 29 while the opposite end thereof is received in a bearing 30, this

latter bearing being provided with a slidably mounted carriage 31 received upon a suitable guideway or bracket 32. Thus, it will be understood that that end of the countershaft 28 engaged in the slidable bearing 30 will be permitted to be moved but at the same time, it will be appreciated that the extent of such movement will not be such as to disengage the meshing gears 26 and 27.

10 A friction wheel 33 is also fixedly mounted upon the countershaft 28, preferably at a point in proximity to the mounting of the aforesaid end of such shaft in the slidable bearing 30; this friction wheel 33 being adapted to be engaged with a friction pulley 34 fixedly mounted upon an adjacent portion of a driving shaft 35, also mounted in bearings 36 upon the said frame 25 and arranged in substantially parallelism to the aforesaid shafts 23 and 28. A fly wheel 37 is provided upon this driving shaft 35 and is adapted to have belt gearing or similar power transmitting gearing 38 engaged therewith in the manner indicated in the figures 2 and 3, this belt gearing 38 being extended from a suitable source of power, not shown herein. Thus, it will be appreciated that with the transmission of rotary motion by way of the belt gearing 38 to the driving shaft 35, such motion will be transmitted from the friction pulley 34, to the friction wheel 33, then from the counter shaft 28 to the driven shaft 23 by way of the meshing gears 26 and 27. From here, such rotary motion will be transmitted by way of the endless sprocket chain 21 to the shaft 11, hereinbefore described, in order that rotary motion will be delivered or transmitted to the endless conveyor chains 13 of the auxiliary transfer device. To normally maintain the peripheral portion of the friction wheel 33 in engagement with the periphery of the friction pulley 34, a lever 39 is mounted upon one end of the bracket 32 as indicated at 40, the upper end of this lever being engaged by one end of a contractile coiled spring 41, the opposite end of which is adjustably secured through the medium of a bolt 42 to an adjacent portion of the super-supporting structure 4. Obviously, by adjusting this bolt 42 with respect to the super-supporting structure 4 with which it is engaged, the tension of the contractile coil spring 41 may be either increased or decreased and thus, it will be understood that the pressure with which the peripheral portion of the friction wheel 33 is engaged with the periphery of the friction pulley 34 may be regulated as required.

15 As intimated, since the upper or free end of the lever 39 is engaged by the contractile coil spring 41, the lower portion of said lever will be normally maintained in its inward position and thus, due to the fact that said lever is connected through the

medium of a link 43 with the bearing carriage 31, the bearing 30 thereon will be normally arranged in a position so that the peripheral portion of the friction wheel 33 is engaged with the periphery of the friction pulley 34. However, while rocking the lever 39 in an opposite direction, it follows that a pull will be imparted to the bearing carriage 31 and by consequence, that this particular end of the countershaft 28 will be moved so as to disengage the peripheral surface of the friction wheel 33 from the periphery of the friction pulley 34, hence, interrupting the transmission of rotary motion from said pulley 34 to the wheel 33. Thus, with disengagement of the lever 39, the contractile coil spring 41 will immediately serve to return it to its normal position whereat frictional contact as between the elements 33 and 34 will be re-established and a power transmitting connection thus effected as between the shafts 28 and 35.

20 Automatic means are provided for imparting rocking motion to the lever 39 in form of an air or steam cylinder 44, the basal portion of which is secured to an appropriate portion of the super-supporting structure 4 in the manner shown in the Figure 2. A piston is received within this cylinder and to the outer end of its rod there is pivotally joined a connecting rod 45, which in turn, has its free extremity pivotally connected to a portion of the said lever 39 as indicated at 46. An air or steam inlet connection 47 is provided the cylinder 44 and to control the discharge of air or steam into said cylinder at the will of an operator, a control valve 48 is interposed therein, the stem of said control valve having an operating lever 49 connected thereto, which in turn is pivotally connected with a rod 50 extending into pivotal engagement with one end of a bell crank lever 51 mounted upon a suitable supporting arm 52; the opposite end of this bell crank lever 51 being pivotally connected to the lower end of a foot lever or plunger 53, the upper end of which is passed through a supporting platform 54 received upon the super-supporting structure 4 and 5 in the manner as shown in the Figures 1 and 2. Upon this platform 54, the operator or attendant of the device is adapted to stand and by consequence, this said operator may interrupt the transmission of rotary motion to the endless conveyor chains 13 of the auxiliary transfer device, by only placing his foot upon the plunger 53, depressing the same so as to rock the bell crank lever 51, and the control valve 48 will be opened to admit air or steam to the cylinder 44. With the admission of air or steam to the cylinder 44, an outward thrust will be imparted to the piston working therein and by consequence, such outward thrust will be delivered by

way of the connecting rod 45 to the lever 39, hence, rocking said lever 39 in a direction to move the slidable bearing 30 in such a manner as to effect a disconnection of the 5 peripheral surface of the friction wheel 33 with the peripheral surface of the friction pulley 34. Hence, transmission of rotary motion from the driving shaft 35 to the countershaft 28 will be interrupted for the 10 time being. When however, the operator disengages or removes his foot from the plunger 53, said plunger will return to its normal position and the valve 48 will, by consequence, be closed, thus permitting the 15 air within the cylinder 44 to be exhausted and allowing the piston working therein to be returned to its normal inoperative position by reason of the counter-action of the contractile spring 41 engaging the upper or 20 free end of the lever 39. With the return of the piston within the cylinder 44 to its normal position, repositioning of the slid- 25 able bearing 30 will be effected and by consequence, a frictional driving connection be- 30 tween the shafts 28 and 35 will be re-established. In this way, it is manifest that the transmission of rotary motion to the endless conveyor chains 13 of the auxiliary transfer device may be controlled at will by an operator.

Also, if desired, another control plunger 55 may be extended to the supporting platform 54 and this plunger 55 is connected to control mechanism, not shown herein, in 35 order that the said operator may control the transmission of motion to the endless conveyor chains 2 of the standard transfer table.

The operation of our improved device 40 may be reviewed as follows:

Rotary motion is transmitted to the endless conveyor chains 13 of the auxiliary transfer device through the motion transmitting mechanism hereinbefore described.

45 Likewise, motion is transmitted to the conveyor chains 2 of the transfer table 1 in the usual manner. Sawed boards are carried by the conveyor chains 2 of the transfer table 1 to positions whereat they will be engaged 50 by the properly moving endless conveyor chains 13, such sawed boards being conveyed from the discharge end of the transfer table 1 and elevated to positions above the same as is indicated in the Figure 2.

55 The boards so conveyed and elevated are directed onto the horizontally arranged portion 16 of the runway from whence they are directed onto the skidding bars 17. As the boards are directed onto the skidding bars 60 17, the operator standing on the platform 10

properly adjusts the same so that the adjacent end of the board in process of being transferred will be properly positioned with respect to the first trimming saw 7' of the 65 series of trimming saws shown in the Figure

1. This adjustment may be readily effected by the operator aforesaid, merely by pushing or pulling the board being transferred over the skids 17 to a position whereat the end to be trimmed will be properly arranged 70 with respect to said first trimming saw 7'. Consequently upon this adjustment of the sawed board by the operator upon the platform 10, it will be appreciated that with the following cutting of the board to the desired length by the trimming saws 7 and 7', the respective ends thereof will be properly squared. As the operator may desire, the transmission of motion to the endless conveyor chains 13 of the auxiliary transfer device 75 may be controlled. Likewise, the motion of the conveyor chains 2 of the transfer table 1 may be also controlled by reason of the localizing of the control devices in form of the plungers or foot levers 53 and 55 upon 80 the said platform 10. Through the provision of this improved auxiliary transfer device, it will be understood by persons skilled in the art that we are enabled to dispense with the services of the second man usually 85 employed in the transfer of boards from the transfer table onto the trimming table. Likewise, the work of this operator standing upon the platform 10 will be reduced to minimum by reason of the fact that the 90 boards being transferred from the table 1 onto the trimmer of the sawmill will move by gravity over the downwardly inclined portions of the various skid bars 17 and that during this skidding transfer of the 100 boards from the table onto the trimmer, proper adjustment of the same with respect to the trimming saws 7 and 7' may be effected. Also, because of the localizing of 105 the controls for the conveyor chains 2 and 13, the operation or feed of sawed boards from the transfer table 1 onto the skidding bars 17 may be controlled at the will of the operator.

Manifestly, the construction shown is capable of considerable modification, and such modification as is within the scope of our claims, we consider within the spirit of our invention.

We claim:

1. In combination, a trimmer table, a transfer table, and conveying means therebetween consisting of inclined bars, each having a portion thereof horizontally disposed.

2. In combination, a trimmer table, a transfer table, and conveying means therebetween consisting of inclined bars, each having horizontally offset portions formed upon their upper ends.

It witness whereof we have hereunto set our hands.

CARL MOSEN.
WILLIAM J. COLEMAN.
